CENTRIFUGAL BLASTING MACHINE

Lloyd L. Hobson, Marshall, Mich., assignor to
 The American Foundry Equipment Company,
 Mishawaka, Ind., a corporation of Delaware

Application August 21, 1939, Serial No. 291,111

19 Claims. (Cl. 51—9)

This invention relates to centrifugal blasting machines, and more particularly to an improved blasting machine of the centrifugal type from which abrasive can be fired in any desired controlled clockdial direction and concentrated in any desired work zone.

In accordance with this invention, an abrasive throwing rotor is fixed to a suitable drive shaft which is driven in timed relation to the shaft of a control runner positioned within the rotor. The rotor may comprise a suitable rotor head equipped with any desired number of equally spaced throwing blades or segments which define abrasive discharge passageways or ports therebetween. The throwing blades or segments may be removably mounted upon the rotor head in such manner that they may be easily replaced when worn. The throwing blades or segments of the rotor may be of any desired radial length, stopping short of the axis of rotation thereof a sufficient distance only to provide room for the control runner seating therein.

The control runner may comprise a suitable runner head fixed to a drive shaft provided therefor, the runner head being likewise equipped with equally spaced abrasive discharge blades or segments defining abrasive discharge passages or ports therebetween. The blades or segments of the control runner may also be detachably secured to the runner head so that they may be removed and replaced when worn. The blades or segments of the control runner may be of any desired radial length, but preferably the inner ends thereof should stop short of the axis of rotation of the runner to provide a central space into which abrasive may be fed from a suitable abrasive supply conduit. The axis of rotation of the control runner is concentric with the axis of rotation of the throwing rotor, both the throwing rotor and control runner being driven in predetermined timed relation and preferably from a common drive connected to a suitable source of power, such as an electric motor.

The number of passages or blades provided on the control runner should be either greater or less than but not equal to the number of blades or discharge passageways provided on the throwing rotor. Where it is desired to obtain directional discharge over one section of the rotor only, the number of blades or discharge passages in the control runner is preferably either one less or one more than the number of blades or discharge passages in the throwing rotor. The rotor shaft and runner shaft are operably connected by means of a suitable drive transmission

so that a drive ratio between these two shafts which is in inverse ratio to the number of blades or discharge passages in the runner and rotor is at all times maintained. Assuming, for example, that the rotor is provided with eight throwing blades or discharge passages and the runner is provided with nine blades or discharge passages, and assuming further that an effective blasting speed can be attained with this machine when the rotor is rotated at 2250 R. P. M., the runner should then be rotated at 2000 R. P. M. If this inverse ratio is at all times maintained, the blades or abrasive discharge passages in the runner can be moved into discharging alignment with the discharge blades or passages in the rotor at a predetermined clockdial position, so that the machine will fire the abrasive over a predetermined clockdial sector during rotation thereof. When it is desired to discharge the abrasive from two sections of the rotor, the number of blades or discharge passages in the control runner is preferably either two less or two more than the number of blades or discharge passages on the throwing rotor so that the blades or discharge passages in the control runner and throwing rotor will move into discharging alignment at two positions, as, for example, the 12 o'clock and the 6 o'clock positions. The necessary fixed drive ratio between the rotor shaft and runner shaft can be maintained by positive interconnecting drives between these shafts and rotating both shafts from a common power source. The drive transmission between the rotor shaft and runner shaft may take the form of intermeshing gears, chain and sprocket drives, "Morse" drives, or any other positive drive mechanism which will maintain the required drive ratio.

The equally spaced discharge passageways in the runner may take the form of simple outlet ports formed in the tubular side wall of a tubular member. The discharge passages in the rotor may likewise comprise discharge ports formed in a relatively thick rotor ring, but preferably the throwing face of these discharge ports should be of sufficient length to receive abrasive thereon and forcibly impel the abrasive forwardly during rotation of the machine at a blasting velocity.

The throwing rotor, as well as the control runner, may be made in numerous different shapes and forms within the purview of this invention. The blades, throwing segments, discharge passages or discharge ports, in the rotor and runner may be made of almost any desired radial length and almost any desired number thereof may be provided ranging from one to fifty or more. Sub-

stantially the only essential criterion that must be followed is that the blades or segments, passages or ports in the control runner must be either more or less than the blade segments, passages or ports in the throwing rotor and, further, that the runner and rotor must be driven in substantially positive timed relation so that the abrasive discharge passages or ports in the runner will advance ahead or drop back into alignment with the discharge passages or ports in the rotor at the predetermined clock-dial position or positions during timed rotation thereof to effect the desired directional discharge of the fired abrasive.

Directional control adjustment can be effected by readjusting the position of the runner on its drive shaft, by readjusting the position of the rotor on its drive shaft, or by readjusting the sprockets, gears, or other positive drive mechanism that operably connects the runner shaft with the rotor shaft.

By reason of the fact that the runner rotates at only slightly less or slightly greater speed than the rotor and in the same clock-dial direction, abrasive transfer from the runner to the rotor can be effected substantially without shock or impact to the advancing faces of the rotor blades or segments. Thus abrasive wear on the inner ends of the advancing rotor blades or segments is at a minimum and little or no break-up or destruction of the abrasive results during its passage through the machine. The machine is so constructed that the abrasive is distributed uniformly over the entire width of the rotor blades or segments, producing even and uniform wear thereon with correspondingly greater life thereof, and, finally, an impingement pattern of full rotor blade width is produced. Directional firing of the abrasive ejected from the rotor may be controlled to a great nicety and within 5° or less, if desired. Little or no scattering of the abrasive around the undesired sections of the rotor results. An unusually high degree of directional control is produced. The length of the blast pattern may be varied by enlarging the circumferential length of the passages in the rotor or runner or both. With corresponding enlargement of the passages in the runner and rotor which lengthens the impingement pattern, a greater quantity of abrasive can be thrown, so that substantially uniform abrasive intensity throughout the length and width of the impingement pattern is also attained, even though a relatively long impingement pattern is made. This highly important result has never been attained in centrifugal blasting machines now known or in use. The machine runs smoothly and silently, maintains excellent dynamic balance, and will clean and treat the surfaces of castings, forgings, bars, sheets, and other like hard surface materials, with high efficiency and at low cost.

An object of this invention is to provide a centrifugal blasting machine having improved means for controlling the direction of discharge of abrasive fired therefrom.

Another object of this invention is to provide a centrifugal blasting machine in which wear on the operating parts thereof by reason of contact with moving abrasive is reduced to a minimum, with substantially no break-up, destruction or damage of the abrasive resulting during its passage through the machine.

Another object of this invention is to provide a centrifugal blasting machine in which directional firing of the thrown abrasive can be con-

trolled to a nicety and which can be made to produce a blast pattern on the target of any desired width and length, which pattern is characterized by uniformity in blast over the entire surface thereof.

Other objects and advantages of this invention will become apparent as the disclosure proceeds.

The invention also consists in certain new and original features of construction and combination of parts hereinafter set forth and claimed.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawings forming a part thereof, in which—

Fig. 1 is a side elevational view of one form of improved abrasive throwing machine showing the mountings and drives for the throwing rotor and control runner, certain parts being shown in section to illustrate the construction;

Fig. 5 is a front face view of the throwing rotor and control runner as it appears when looking in the direction of the arrows 5—5 of Fig. 4, certain parts being broken away to illustrate certain features of the construction;

Fig. 6 is a transverse cross-sectional view through an abrasive throwing machine, showing a throwing rotor and control runner and drives therefor of further modified construction;

Fig. 7 is a cross-sectional view through the throwing rotor and control runner as it appears when looking in the direction of the arrows 7—7 of Fig. 6;

Fig. 8 is an enlarged transverse cross-sectional view of certain parts of the throwing rotor and control runner shown in Fig. 6 as they appear when looking in the direction of the arrows 8—8 of Fig. 6;

Fig. 9 is a perspective view of a throwing blade which may be associated with the throwing rotor shown in Fig. 6;

Fig. 10 is a cross-sectional view through a throwing rotor and control runner of the type shown in Figs. 6 and 7 modified to the extent that the control runner is provided with discharge passages arranged to align with discharge passages of the throwing rotor at two diametrically opposed points during operation whereby two oppositely directed streams of abrasive will be simultaneously fired by the machine; and

Fig. 11 is a cross-sectional view through a throwing rotor and control runner of the type illustrated in Figs. 1, 2 and 3, except that the control runner is provided with discharge passages which align with discharge passages in the

throwing rotor at two diametrically opposed points during operation of the machine whereby abrasive may be fired from the machine in two directions simultaneously during the operation thereof.

Similar reference characters refer to similar parts throughout the several views of the drawings and specification.

Referring more particularly to Figs. 1 to 3 inclusive, a throwing rotor 10 is illustrated fixed to shaft 24, rotated by pulley 30 operatively connected to a suitable source of power, as an electric motor, by means of a V-belt drive. A control runner 40 mounted upon a shaft 55 is operatively connected to be driven in timed relation with shaft 24, and rotor 10. As more particularly illustrated in Fig. 3, the throwing rotor 10 is provided with a plurality of equally spaced abrasive discharge passageways 15, which are shown for purposes of illustration as sixteen in number. The control runner 40 is also provided with equally spaced abrasive discharge passages 45 which may be greater or less in number than the discharge passages 15 in the throwing rotor but shown in Fig. 3, for purposes of illustration only, as seventeen in number. The speed of rotation of the control runner 40 with respect to the throwing rotor 10 is such that the discharge passages therein will rotate into alignment in the desired clock-dial position so as to effect controlled directional firing of the abrasive ejected from the throwing rotor 10.

The throwing rotor 10, as shown in Figs. 1 to 3 inclusive, may comprise a side wall member or rotor head 11 having a plurality of blades or segments 12 mounted on the periphery thereof, which are spaced apart so as to provide abrasive discharge passageways 15 therebetween through which the abrasive may be freely discharged. The blades or segments 12 may have any desired radial length short of the axis of rotation of the throwing rotor, so as to provide a central space within which the control runner 40 may be positioned. The throwing blades of segments 12 may be cast as a part of the side wall member 11 or they may be suitably secured thereto so that the blades may be removed when worn, as desired. A ring member 13 is provided which is connected to the free ends of the blades or segments 12, as by screws 14, to stiffen and strengthen the construction.

Assuming that the throwing rotor 10 and control runner 40 is to be rotated in the direction of the arrow shown in Fig. 3, each blade or segment 12 is provided with an advancing throwing face 15' and a following face 15'', so that the advancing face 15' and following face 15'' of blades or segments 12 define an abrasive passage 15 therebetween. Each blade or segment 12 may also be provided with an abrasive-retaining cavity 16 defined between abrasive-retaining end wall portions 17 and 18, for a purpose that will presently appear.

The throwing rotor 10 is fixed to a hub member 20, as by securing bolts 21 screwed into the side wall member 11 thereof. The hub 20 is provided with an internal bore 22 into which the end of drive shaft 24 extends, the hub 20 being secured to drive shaft 24 as by spline 23. The shaft 24 is rotatably mounted in spaced bearings 25, each supported by suitable supporting frames 26 and 27 respectively. Each bearing 25 is held in fixed position by means of a bearing cap 28 bolted to each supporting frame, as by bolts 29. The shaft 24 and the throwing rotor 10 is rotated

at the proper desired driving speed by means of the V-belt pulley 30 fixed to the drive shaft 24.

The control runner 40 may comprise a side wall member or runner head 41, which is positioned within the central space within the throwing rotor 10. Blades or segments 42, defining abrasive discharge passageways 45 therebetween, may be integrally formed with the side wall member 41 or may be removably secured thereto in any desired manner. The front face of the control runner is substantially closed by a side wall plate 43 secured to each of the blades or segments 42, as by screws 44. The closure plate 43 is provided with an axially extending aperture 53 therein through which drive shaft 55 for the runner head extends and through which aperture abrasive *a*, supplied by the feed funnel 81, may be injected into the central space 54 between the side wall member 41 and the closure plate 43 of the control runner 40.

The inner face and the passage-defining walls of the blades or segments 42 may be covered with a liner of abrasive resistant material, as shown more particularly in Fig. 3, each liner having an inner facing portion 46 and passage liner portions 47 and 48. The liner portion 47 defines the advancing face of the blade or segment and the liner portion 48 defines the trailing or following face thereof. Each blade or segment 42 may be provided with an outwardly facing cavity 49 defined between retaining end walls 50 and 51.

The side wall member 41 of the control runner 40 may be provided with an axially extending internal hub portion 52 through which the drive shaft 55 extends. The hub portion 52 may have a generally cone-shaped contour so as to deflect the abrasive discharge into the control runner 40. The hub portion 52 is secured to the drive shaft 55 by means of a suitable spline 56.

The reduced end 55' of shaft 55 extends into the hub 20 of the throwing rotor 10 and is rotatably mounted therein by means of a suitable bearing which may comprise bearing raceway member 58 fixed to the reduced end 55' of shaft 55. Roller bearings 59 roll in raceway member 58 and a raceway member 60 fixed to the interior of hub 20. The shaft bearing may be held in position by means of a cap plate 61 screwed into the hub 20, as shown in Fig. 1. The end of shaft 55 extends through a suitable opening 57 in the side wall member 11 of the throwing rotor 10 and is supported in the bearing housed within the hub 20. The other end of the shaft 55 is rotatably supported in a suitable bearing 63 carried by supporting frame 64, the shaft 55 being held in position by a bearing cap 65 removably secured to the frame support 64 by bolts 66.

The control runner shaft 55 may be operatively connected to be rotated by the drive pulley 30, as by means of a sprocket 67 fixed to shaft 55, over which is trained a drive chain 68 trained over transmission sprocket 69. Transmission sprocket 69 is fixed to the end of a power transmission shaft 70 supported in spaced bearings 71, each supported upon a suitable bracket support 72. The shaft 70 and its bearings 71 are held in operative position by means of bearing caps 73 secured as by bolts 74 to their respective supporting brackets 72. The shaft 70 is provided with a suitable drive sprocket 78 secured to the opposite end thereof, over which is trained a drive chain 79 extending around sprocket 80 fixed to the shaft 24 of the throwing rotor 10. By means of the drives above provided, it will be appreciated that both the throwing rotor 10

and the control runner 40 may be driven simultaneously and in synchronized relationship from the drive pulley 38.

Abrasive is supplied to the interior space 54 of the control runner 40 by means of an abrasive supply pipe or chute 81 having a collar 82 extending into the opening 53 in the front wall plate 43 of the control runner 40. The lower arcuate portion 83 of the collar portion 82 may be inclined downwardly to permit the abrasive a to smoothly slide into the abrasive-receiving interior 54 of the control runner 40. The feed spout 81 may be suitably supported in fixed position by means of a bracket 84 connected to the feed spout 81 and suitably secured to a stationary bracket or frame member 85 positioned exterior of the control runner 40.

It will be appreciated that the abrasive fed into the interior 54 of the control runner 40 falls downwardly by the action of gravity into the discharge passages 45 of the control runner 40 during rotation thereof. The abrasive driven outwardly by centrifugal force occupies the interior of the discharge passages 45 and additional abrasive which cannot occupy the filled passages 45 clings, through the action of the centrifugal force, to the interior wear surfaces 46 of the throwing blades or segments 42.

The abrasive driven outwardly by centrifugal force into the discharge passageways 45 of the control runner 40, will also fill the cavities 16 provided at the inner periphery of the throwing segments 42 during rotation of the runner 40. The relative speed differential between the throwing rotor 10 and the control runner 40 is small, so that no excessive friction is set up between the inner periphery of the blade segments 42 of the throwing rotor 10 and the outer periphery of the blade segments 42 of the control runner 40. The pockets 16 in the blade segments 42, which are normally filled with abrasive during operation, and the pockets 49 of the blade segments 42, which are normally free of abrasive because of the outward drive of the centrifugal force exerted on the abrasive, have a marked effect in reducing frictional wear between the moving blade segments 42 of the throwing rotor 10 and control runner 40 and further prevent discharge of abrasive from the throwing rotor 10 in undesired directions.

The control runner 40 and the throwing rotor 10 are driven at such differential speeds as to cause the discharge passageways 45 and 15 thereof to move into alignment to permit discharge of the abrasive through the aligned passageways 45 and 15 at a predetermined clock-dial position. This is effected by rotating the control runner 40 and throwing rotor 10 at a speed differential which is determined by the relative number of discharge passageways 45 and 15 therein. The discharge passageways 15 and 45 in the throwing rotor 10 and control runner 40 may be almost any desired number except that the control runner 40 must either have more or less discharge passages than the number of discharge passages in the throwing rotor 10.

By way of example, there is shown in Fig. 3 a control runner 40 having seventeen equally spaced discharge passageways 45 therein, while the throwing rotor 10 has sixteen equally spaced 70 discharge passageways 15 therein. It will be appreciated that if the throwing rotor 10, equipped with sixteen discharge passages 15, is rotated at 1700 R. P. M. and the control runner 40, equipped with seventeen discharge passageways 45, is ro-

tated at 1600 R. P. M., the respective passages 15 and 45 thereof will move into alignment at a predetermined clock-dial position, so as to permit discharge of abrasive through the aligned openings. The advancing faces 15' of the rotor blade segments 42 operate to hurl or throw abrasive approximately tangentially from the periphery of the rotating throwing rotor 10. This speed differential may be obtained by making the sprockets 78 and 89, which drive the control runner shaft 55, of the proper relative tooth ratio to effect this result. Since the speed differential between the control runner 40 and the throwing rotor 10, in the machine disclosed in Fig. 3, may be only 100 R. P. M., no serious wear on the adjacent faces of the moving blade segments of the control runner 40 and throwing rotor 10 results.

It will be appreciated that both the outside and inside diameters of the throwing rotor 10 may be of any size desired, the outside diameter of the control runner 40 being correspondingly reduced or enlarged. Thus, the throwing faces 15' of the blade segments 42 may be of any desired length to effect projection of the abrasive at the desired blasting velocity, the speed of rotation of the throwing rotor 10 as well as its diameter being such as to give the abrasive thrown therefrom the desired blasting speed. The direction of discharge from the throwing rotor 10 may be controlled by so adjusting the position of the discharge passageways 45 of the control runner 40 that one of the passageways 45 will move into alignment with one of the discharge passages 15 of the throwing rotor 10 as that discharge passage arrives at the desired clock-dial position, which may be effected by shifting the secured position of the runner 40 on its shaft 55, by shifting the secured position of the rotor 10 on its shaft 24, or by shifting the secured position of sprockets 87, 89, 78 or 80 on their respective shafts.

The throwing rotor 10 may be rotated at any desired blasting speed, the rotating speed of the control runner 40 being correspondingly timed to effect alignment of the respective passages therein at the selected clock-dial position. Full, complete and positive control of the direction of discharge of the thrown abrasive and high blasting efficiency with relatively little wear on the parts, is obtainable by the machine above described.

A centrifugal abrasive blasting machine constructed in accordance with this invention may take other forms than that shown in Figs. 1 to 3 inclusive. For example, there is shown in Figs. 4 and 5 a centrifugal blasting machine of somewhat modified construction, comprising a throwing rotor 100 having radially extending discharge passageways 106 defined between blade segments 102 of greater radial length than that shown in the throwing rotor 10 shown in Fig. 3. The control runner 130, as shown in Figs. 4 and 5, positioned within the throwing rotor 100, is of correspondingly reduced diameter and is provided with discharge passageways 136 defined between sector-shaped blade segments 132. The throwing rotor 100 may be fixed to a hollow shaft 116 rotatably mounted upon suitable bearings, and the control runner 130 may be fixed to a solid shaft 138 extending through hollow shaft 116, the shafts being operatively connected by means of suitable gearing contained within a gear housing 158. A pulley wheel 123, over which may be trained a V-belt drive, is fixed to the hollow shaft 116 by means of a suitable spline 124, so

that both the rotor shaft 116 and the runner shaft 139 may be rotated in proper synchronized relationship from a single power source.

The throwing rotor 100 may comprise a side wall member 101 upon which the throwing blades or segments 102 may be removably mounted. There is shown in Fig. 5, for purposes of illustration, eight blades or segments 102 equally spaced apart to provide abrasive discharge passages 106 therebetween. A closure ring or cover plate 103 may be provided to close the front face of the throwing rotor 100; face plate 103, the throwing blades 102 and side wall member 101 being suitably secured together as by threaded bolts 104. The interior surface of the side wall member 101 and the closure member 103 may be provided with suitable grooves 105 to receive and maintain the blades or segments 102 in proper spaced relationship.

Assuming that the throwing rotor 100 and control runner 130 rotate in the direction of the arrow shown in Fig. 5, the advancing face 107 of each blade or segment 102 provides an abrasive throwing face or surface over which the discharging abrasive moves, the following face 108 of each segment along with the advancing face 107 of the following segment defining the abrasive discharge passage 106 therebetween. The faces 107 and 108 of each segment 102 and the abrasive discharge passages 106 may be of any desired radial length, extending inwardly a sufficient distance short of the axis of rotation of the rotor 100 to provide only sufficient space for the control runner 130.

The inner peripheral surface of each throwing segment 102 is provided with an inwardly facing cavity 109 defined by end riser walls 110 and 111 adjacent each discharge passageway 106. Abrasive *a* is free to collect in the cavity 109 but due to the riser walls 110 and 111 will not discharge into the discharge passageways 106 until abrasive is supplied to the discharge passageway 106 in the throwing rotor 100 at the desired predetermined clockdial position when abrasive passages 136 of the control runner 130 move into alignment therewith, as will be presently described.

The throwing rotor 100 is mounted upon a suitable hollow hub 114 and secured thereto by bolts 115 screwed to the side wall member 101. The hollow rotor-supporting shaft 116 extends into the hub bore and is secured thereto by means of a suitable spline 117. The hollow rotor shaft 116 is supported by a pair of suitable spaced brackets 118 and 119 each having one or more ball bearing mountings for the shaft 116, comprising raceway collars 120 fixed to the shaft 116, raceway collars 122 carried by its supporting bracket, and ball bearings 121 which move in the raceway collars 120 and 122.

The control runner 130 comprises a side wall member 131 supporting V-shaped blade segments 132 which are equally spaced to provide therebetween nozzle-shaped abrasive discharge passageways 136 defined by the advancing face 134 of one segment 132 and the following face 135 of the preceding segment 132. The blade segments 132 may be integrally formed with the side wall member 131 or may be removably secured thereto by suitable bolts or screws. The control runner 130 fits within the throwing rotor 100, and the open face thereof may be closed by a suitable closure plate 133 formed integrally with or otherwise secured to the blade segments 132. 75

The apex end of the blade segments 132 extend inwardly short of the concentric axis of rotation of the throwing rotor 100 and control runner 130, and front closure plate 133 is provided with a suitable opening 137 into which the discharge end of abrasive supply spout 150 extends. Abrasive *a* is discharged from the discharge spout 150 into the central space 138 within the control runner 130 where the abrasive collects and is driven by centrifugal force into the discharge passageways 136 thereof.

The control runner 130 is fixedly mounted upon a suitable shaft 139 extending through the hollow rotor shaft 116, the reduced end 140 of shaft 139 extending into a cup-shaped hub portion 141 which may be formed as an integral part of side wall member 131, the reduced end 140 of the shaft being secured to hub portion 141, as by spline 141'.

20 The runner end of the shaft 139 is rotatably supported within the hollow shaft 116 by means of a suitable bearing comprising raceway collar 142 fixed to the shaft 139, raceway collar 144 fixed to the hollow interior of rotor hub 114, raceway collars 142 and 144 having ball bearings 143 rollable therebetween. The shaft 139 may be provided with an enlarged boss portion 145 to retain the bearing in proper position. The opposite end of shaft 139 may be likewise supported by a suitable roller bearing comprising raceway collar 146 fixed to shaft 139, raceway collar 148 fixed to the interior of hollow rotor shaft 116 with roller bearings 147 in position to roll between these raceway collars.

35 Means are provided for operatively connecting rotor shaft 116 to rotor shaft 139 so that they can be driven in the proper timed relationship. As shown more particularly in Figs. 4 and 4a, a driving gear 155 is fixed to the end of rotor shaft 116, which driving gear meshes with transfer gear 156 fixed to shaft 157. Shaft 157 is free to rotate in suitable bush bearings 159 and 163 provided respectively in a gear casing 158 and a gear casing enclosing plate 161. A transfer gear 164 also fixed to rotating spindle shaft 157 is arranged to mesh with gear 165 fixed to the end of the runner shaft 139. The gear housing 158 may be provided with a suitable flange 160 by means of which it may be secured to the adjacent shaft-supporting bracket 119. The gear housing enclosing plate 161 may be removably secured to the gear housing 158 by means of suitable lag screws or bolts 152, giving free access to the train of gears therein. Thus the driving mechanism for rotor shaft 116 and runner shaft 139 is completely enclosed, and grease or lubricating oil in the space 149 within the hollow shaft 116 and the space 166 within the gear box casing 158 is kept in constant agitation by the moving parts to lubricate the gears and shaft-supporting bearings therein.

To illustrate the adaptability of this machine to various operating conditions, there is more particularly illustrated in Fig. 5 a throwing rotor having eight discharge passages 106 and a control runner having seven discharge passages 136. Assuming, for example, that the throwing rotor 100, with eight discharge passageways, has a diameter which will give the abrasive fired therefrom the desired blasting velocity when rotated at 2100 R. P. M., it will be appreciated that if the control runner, provided with seven equally spaced discharge passages 136, is rotated at 2400 R. P. M., each discharge passage 136 in the runner will move into discharging alignment with

one of the discharge passages 106 in the rotor at a predetermined clockdial position so as to effect the desired directional discharge of the fired abrasive. It will be further noted, by referring to Fig. 5, that, except during the desired discharging arc, the runner passages 136 will be out of alignment with the rotor passages 106 so that no abrasive will be discharged through the discharge passages 106, discharge taking place only when the successive passages 136 move into partial or full alignment with successive passages 106.

The desired differential rotative speed between the control runner 130 and the throwing rotor 100 with a discharge passage ratio of eight to seven, as shown in Fig. 5, may be attained by providing the transfer gear 156 and drive gear 165 with a lesser number of teeth than has transfer gear 164 and drive gear 155, as in the ratio of eight to seven in the construction illustrated, so that the drive pulley 123 will drive rotor shaft 116 at 2100 R. P. M. and will drive runner shaft 139 at 2400 R. P. M. In all cases the required speed ratio between the runner shaft and the rotor shaft to obtain discharging alignment of the passages therein at the desired clock-dial position, will of course be determined and computed on the basis of the number of equally spaced discharge passages in the rotor as compared to the number of equally spaced discharge passages in the runner. Any desired passage ratio and corresponding speed ratio may be selected, as will be fully evident to those skilled in the art.

The abrasive supplied to the runner 130 by the feed pipe 150 will be distributed during rotation of the runner 130 into the discharge passages 136 so as to maintain approximately the same amount of abrasive in each passage, but obviously an excessive quantity of abrasive, which would choke the interior of the runner, is not desirable. It will be appreciated that almost any desired quantity of abrasive, from 100 to 1000 lbs. of abrasive per minute and over, can be fed through the machine by merely enlarging the discharge passageways 136 of the runner 130 and enlarging the discharge passages 106 in the rotor 100. The abrasive pockets 109 do not interfere with the proper rotative movement of the runner 130 or rotor 100, and since the speed differential between the rotor 100 and runner 130 is so small, no serious frictional wear results. The abrasive is retained within the pockets 109 by centrifugal force but the pockets 167 on the exterior face of the runner segments 132 are normally free of abrasive during operation because of the action of centrifugal force. Pockets 167 in each runner segment 132 are defined by the raised end walls 168 and 169 thereof. Since the peripheral length of the riser walls 110 and 111 of the rotor segments 102 and the riser walls 168 and 169 of the runner segments 132 is relatively short, there is no serious frictional wear or grinding between these parts, and any abrasive lodging between these parts is almost immediately moved into the abrasive-receiving cavity 109 or into the discharge passages 106 or 136. To facilitate entry of the abrasive into the receiving cavity 138 of the runner 130, the hub portion 141 thereof may be provided with tapered deflecting surfaces 141' which readily deflect abrasive discharging from the feed spout 150 into the receiving space 138 of the runner 130.

A further modified form of centrifugal abrasive throwing machine is illustrated in Figs. 6,

7 and 8. In this machine the throwing rotor 200 is provided with throwing blades *b* of substantial length, and the control runner 210 is of reduced diameter so that the abrasive discharged in the desired clockdial position upon the inner ends of the rotating blades *b*, is given an opportunity to accelerate over the advancing faces of the blades *b* until it is thrown from the outer ends thereof at a blasting velocity. By making the blades *b* of substantial radial length and the control runner 210 of a small diameter, the linear speed between the inner ends of the blades *b* and the outer periphery of the control runner 210 may be substantially reduced so as to further reduce frictional wear between the relative moving parts thereof.

The throwing rotor 200, as shown in Figs. 6, 7 and 8, may comprise a side wall member 201 and a side wall member 202 spaced therefrom and extending generally parallel from side wall member 201, which side wall members may be connected by suitable spacers 203 having their reduced ends 204 welded, sweated or otherwise secured to the side wall members. Equally spaced radially extending blades *b* are removably mounted between the spaced side wall members 201 and 202, each blade comprising a bottom wall portion 211 and side flange portions 212 which seat within suitable paired grooves 205 provided on the inside faces of the side wall members 201 and 202. The blades *b* may be removably secured in operative position by means of a suitable set screw or screws 214 having a tapered end which seats within a corresponding tapered recess 213 provided in the side edge of the blade *b*. Each set screw 214 may be screwed into a suitable threaded nipple 215 fixed to the side wall member through which it extends.

The side wall members 201 and 202 are each provided with a circular opening whose peripheral edges 221 and 222 respectively are substantially in alignment with the inner ends of the blades *b*. A tubular sleeve member 218 extends into the aligned circular openings in the front and rear side wall members 202 and 201 respectively and is provided with an outturned collar portion 219 which may be secured as by screws 220 to the front side wall member 202 so as to rotate with the blades *b*. The tube 218, as shown more particularly in Fig. 7, is provided with a discharge opening 228 positioned adjacent the advancing face of each blade *b*, the openings 228 defining sleeve segments 218' therebetween. Each abrasive discharge opening 228 is defined by the advancing face 223 of one segment 218' normally positioned substantially in alignment with or slightly in advance of the advancing face of the bottom portion 211 of its associated blade *b*. The following face 224 of each segment 218' defining the other wall of the discharge opening 228 is positioned substantially in alignment with the top edge of the flanges 212 of its associated blade *b*. The inner end of each blade *b* closely abuts against the tubular sleeve 218 so that the abrasive moving out through the discharge openings 228 as they successively advance is positively directed within the channel confines of its associated blade *b*.

The inside face of the tubular sleeve 218 is provided with a plurality of abrasive-receiving pockets 225 each positioned between adjacent discharge openings 228. Each cavity 225, adapted to contain abrasive therein, is defined between end riser walls 226 and 227.

Throwing rotor 200 is rotatably mounted on a

hollow drive shaft 231 by means of a hub 230 into which the end of the shaft 231 extends, the shaft 231 and the hub 230 being fixedly secured together by means of a suitable spline 232. Bolts 233 extending through the flange portion of the hub 230 are screwed into threaded apertures provided in the side wall member 201 of the rotor 200 to fixedly secure the rotor 200 to the shaft 231. To protect the flange portion of the hub 230 from wear resulting from rebounding abrasive, a suitable rubber gasket 234 may be secured to the peripheral edge thereof.

The shaft 231 may be rotatably supported by two spaced paired bearings each comprising a raceway collar 235 fixed to the shaft 231 and a raceway collar 236 supported by the enclosing wall of a suitable bearing housing 237 which is supported by frame members 245. Ball bearings 238 rolling in the raceways provided in collars 235 and 236 permit substantially frictionless rotation of the shaft 231.

The control runner 270 comprises a tubular member, as shown in Figs. 6 and 7, positioned within the control opening in the throwing rotor 200. The control runner 270 comprises a side wall plate 271 secured to the end of runner shaft 290 by means of a bolt 291. A tubular wall 272 formed integral with the side wall plate 271 is provided with nine equally spaced discharge openings 273 therein. The tubular wall portion 272 has a tapered end wall portion 274 which may be of generally cone-shaped contour defining a contracted abrasive inlet opening 275. Abrasive is supplied to the interior of the control runner 270 by means of feed spout 276 which may be provided with an outwardly flared flange portion 277, which serves as a guard protecting the rotating control runner 270.

Abrasive supplied by feed spout 276 to the interior of the control runner 270, is retained by centrifugal force on the interior surface 278 and in the abrasive discharge passages 273 thereof. The discharge passages 273 of the control runner are defined by equally spaced blades or segments, forming the tubular wall 272, each blade or segment having an advancing face 273' and a following face 273''. The abrasive is free to collect in the cavities 225 provided in the segments 218' of the rotor sleeve, the abrasive being confined in these cavities by the end riser walls 226 and 227.

As illustrated in Fig. 7, the throwing rotor is provided with eight equally spaced throwing blades *b* and eight corresponding discharge passageways 228 in the rotating sleeve 218 thereof, while the tubular wall 272 of the control runner is provided with nine equally spaced discharge passageways 273, giving a discharge passage ratio of eight to nine. It will now be appreciated that, if the throwing rotor 200 has a diameter which will give the abrasive discharged from the outer ends of the blades *b* a blasting velocity when rotated at 2250 R. P. M., then if the control runner 270 is rotated at 2000 R. P. M., the discharge passages 273 of the control runner will move into alignment with the discharge passages 228 of the rotor sleeve 218, at a predetermined clockdial arc during rotation, thus effecting controlled discharge of the abrasive from the machine. Since the diameter of the control runner 270 is small, the outer periphery of the tubular wall portion 272 rotates at relatively low peripheral speed, and since the speed differential between the adjacent tubular portion 272 of the control runner and the adjacent tubular portion of the rotor sleeve 218

is only 250 R. P. M., there is no serious wear between these parts. The cavities 225 in the sleeve segments 218' provide a seal for the abrasive contained within discharge passages 273 of the control runner so that no abrasive can escape therefrom except when the rotor and runner passages move into alignment or partial alignment, which alignment occurs at the desired clockdial discharging arc only. Any abrasive which may lodge on the tip ends of riser walls 226 and 227 is driven back into the cavities 225 or permitted to escape through the discharge passages 228 or into the discharge passages 273. Actual test has demonstrated that there is no serious wear between the rotating sleeve 218 of the rotor 200 and the tubular wall 272 of the control runner 270.

Adjustments can be made so that the abrasive discharged from the throwing rotor 200 will be discharged in any desired clockdial direction. This is effected by proper rotative adjustment of the discharge passages 273 in the tubular portion 272 of runner 270 with respect to the discharge passages 228 in the rotor sleeve 218. This desired adjustment can be advantageously effected by providing an internal ring gear 293 which is provided with the desired number of teeth around the interior edge thereof, ring gear 293 being fixed as by screws 293' to a plate 292 which has a square axial hole therein into which the square end 290' of runner shaft 290 extends. The rear side wall member 271 of the runner 270 is likewise provided with a circular gear 294 fixed thereto, as by screws 294' which has teeth on the outer periphery thereof which mesh with the teeth in ring gear 293. By removing bolt 291 which extends through the rear side wall member 271 of the runner 270 and screws into the end of shaft 290, the control runner 270 can be rotated the desired amount and the gear teeth in circular gear 294 pushed into mesh with the gear teeth in ring gear 293. It will be appreciated that ring gear 293 and meshing gear 294 have no relative rotative movement during operation of the machine but they both rotate together with the control runner 270. By providing, for example, seventy-two teeth in the ring gear 293 and plate gear 294, the passages 273 in the runner may be shifted as little as 5° up to 360°, producing a corresponding shift in the direction of discharge of the abrasive from the throwing rotor. Very closely determined directional control adjustments of the machine can thus be attained.

The runner end of runner shaft 290 is rotatably supported within the tubular rotor shaft 231 by means of a suitable bearing comprising bearing runner 296 fixed to shaft 290 and bearing runner 298 fixed to the interior of tubular shaft 231 between which bearings 297 are adapted to roll. Lubricating oil contained within the interior of the tubular shaft 231 is prevented from escaping into the control runner 270 by a suitable oil seal comprising oil gasket 299 which rubs in contact with the runner end of shaft 290 and which is contained within a gasket-receiving collar 300 of channel-shaped cross-section fixed to the interior of hollow shaft 231.

The opposite driving end of runner shaft 290 is rotatably supported within the tubular shaft 231 by means of a roller bearing comprising bearing runner 296 fixed to shaft 290 and bearing runner 298 fixed to the interior of tubular shaft 231, each bearing runner being provided with

raceways within which roller bearings 287 are adapted to roll.

The driving mechanism driving the rotor shaft 231 and the runner shaft 298 in timed relation may be housed within a suitable drive casing 237 supported upon frame members 245. A power transmission shaft 251 is journaled in suitable bearings supported by inwardly extending flanges 260 and 264 formed as a part of the gear housing 237. The inner end 251' of shaft 251 may be of reduced diameter to retain bearing runner 268 fixedly secured thereto. Bearing runner 268 is fixedly secured to the casing flange 266 and ball bearings 257 are positioned to roll between normally stationary bearing runner 258 and rotating bearing runner 256. The other end of shaft 251 is supported in a suitable bearing comprising bearing runner 261 fixed to the reduced end 251'' of shaft 251 and bearing runner 263 fixed to inwardly extending casing flange 264. Ball bearings 262 roll between normally stationary bearing runner 263 and rotating bearing runner 261. The projecting end of shaft 251 carries a drive pulley 250 over which a V-belt drive may be trained, the pulley 250 being secured to the projecting end of shaft 251 as by spline 252.

The drive casing 237 may be capped by a suitable closure 283 having an outwardly extending flange 254 which is suitably bolted or otherwise secured to outwardly extending flange 255 of drive casing 237. The interior space 244 of drive casing 237 is adapted to contain lubricating oil which is kept in constant agitation by the moving parts of the driving mechanism contained therein, which will be presently described. Access to the driving mechanism within the drive casing 237 may be had by removing a closure plate 265 which uncovers an opening 265' in the end wall of the drive casing 237, giving free access to the interior thereof. Closure plate 265 may be bolted to the inturned rim 285' surrounding the opening 265'. The drive end of shaft 251 projects through a shaft opening in cover plate 265, a suitable shaft seal being provided, which is fixed to the flange portion 266 surrounding the shaft opening in cover plate 265. The bearing seal may comprise a stationary gasket 268 which rubs in contact with the shaft 251, the gasket being retained in fixed position by means of a gasket collar 267 of channel-shaped cross-section fixed to the flange portion 266 of cover plate 265.

The power transmission shaft 251 is operatively connected to rotor shaft 231 by means of a "Morse" drive 306 which is trained over drive sprocket 307 fixed to transmission shaft 251 as by spline 308 and trained over sprocket 305 fixed to rotor shaft 231. Runner shaft 298 is also driven from transmission shaft 251 by means of a "Morse" drive 311 trained over sprocket 312 fixed to transmission shaft 251 as by spline 313 and trained over sprocket 301 fixed to the end of runner shaft 298 as by spline 302. A suitable washer 304 and bolt 303 screwed into the end of shaft 298 secures sprocket 301 thereon.

It will now be appreciated that when power is applied to rotate pulley wheel 250, transmission shaft 251 is rotated and "Morse" drive 306 operates to rotate shaft 231 so as to rotate the throwing rotor 200 at the desired abrasive blasting velocity. Runner shaft 298 is rotated in timed relation with rotor shaft 231 by "Morse" drive 311, the proper drive ratio between rotor shaft 231 and runner shaft 298 being attained by providing sprockets 307 and 312 with the required

number of teeth. By way of example, if the throwing rotor 200 having eight throwing blades is set to rotate at 2250 R. P. M., the control runner 270 having nine abrasive discharge passageways 273 would be set to rotate at 2000 R. P. M., which relatively timed rotation is effected by making sprockets 307 and 312 in the drive ratio of nine to eight.

It will be appreciated that the throwing rotor 10 200 may be made in any desired diameter and may be rotated at any desired speed, the control runner 270 being rotated at a corresponding speed ratio determined by the relative number 15 of discharge passageways or blades in the rotor 200 with respect to the discharge passageways in the runner 270. Thus the rotor 200 and runner 270 are rotated at speeds which are in inverse ratio to the number of abrasive discharge ports 20 therein, so that each runner port will line up with a rotor port at the same clock-dial position during rotation. The runner ports and the rotor ports can be so adjusted that alignment thereof occurs at any desired clock-dial position during rotation, by merely adjusting the setting of the 25 control runner 270 and the ports 273 therein with respect to the ports in the rotor sleeve 218.

It will be appreciated that in the several illustrated embodiments of this invention the throwing rotor may be provided with any desired number 30 of throwing blades or discharge passages, and a high degree of directional control can be continuously maintained by providing a control runner having either a greater or lesser number of discharge passages, preferably providing the control runner with either one more or one less discharge passage than those provided in the throwing rotor, if abrasive firing from a single selected clock-dial position is desired. The abrasive may be fired from the throwing rotor in any 35 desired clock-dial direction by a proper mathematical adjustment of the control runner with respect to the throwing rotor.

Assuming, for example, that the throwing rotor 40 is provided with eight equally spaced discharge 45 passageways or blades and the control runner is provided with nine equally spaced discharge passages or blades, as shown in Fig. 7, and that it is desired to shift the direction of discharge from a normally downward or six o'clock position to a normally sideways or three o'clock position, with the rotor and runner rotated clockwise. This control adjustment can be effected by rotating the control runner 270, shown in Fig. 7, so as to bring one of the runner discharge ports 50 55 273 into alignment with one of the rotor sleeve ports 228, at approximately the nine o'clock position. This would require rotation of the control runner 270 a distance of approximately 10° counterclockwise from its position shown in Fig. 7 60 where the runner and rotor parts are shown in alignment at the 12 o'clock position. This assumes, of course, that the rotor blades b are of such length that when the abrasive is moved onto the inner ends thereof at approximately the 65 nine o'clock position, it will be discharged at approximately the three o'clock position. The arc through which the abrasive is carried by the rotor blades or segments after being received on the inner ends thereof and before being discharged therefrom, obviously depends upon various 70 conditions such as the radial length of the rotor blades and the smoothness of the throwing surfaces thereof. The number of degrees that the control runner should be rotated to effect the desired directional discharge can generally be

computed to a mathematical certainty, but the proper adjustment can most readily be determined in actual practice by trial and thereafter from resulting experience with a particular machine.

It may at times be desired to clean castings, forgings, bars and sheets which are positioned on opposite sides of the throwing rotor. My improved centrifugal abrasive throwing machine may be constructed and designed to accomplish this result by providing the machine with a control runner having equally spaced abrasive discharge blades or passages either two more or two less in number than the abrasive discharge passages or ports in the throwing rotor. The control runner and throwing rotor are then rotated in timed relation so that two opposite discharge passages or ports in the control runner will align with two opposite discharge passages or ports in the throwing rotor at two opposed clockdial positions during rotation thereof.

There is shown in Fig. 10 a machine constructed in accordance with the machine shown in Figs. 6, 7 and 8, except that the tubular wall 272 of the control runner 270 is provided with ten abrasive discharge passages or ports 273, the tubular sleeve 218 of the throwing rotor being provided with eight discharge passages or ports 228. Assuming that simultaneous upward firing and downward firing of the abrasive are desired one of the discharge passages 273 of the control runner 270 is brought into alignment with one of the discharge passages 228 of the rotor sleeve 218 at approximately the twelve o'clock position so as to achieve a directed downblast of the abrasive thrown by blade *b*. When this alignment is effected, as shown in Fig. 10, another of the discharge passages 273 of the control runner will align with another of the discharge passages 228 of the rotor sleeve at approximately the six o'clock position so as to achieve a directed upblast of the abrasive thrown by the blades *b*. With the control runner 270 equipped with ten equally spaced discharge passages 273 and the rotor sleeve 218 equipped with eight equally spaced discharge passages 228, controlled firing of two oppositely directed abrasive streams can be effected by rotating the rotor at 2500 R. P. M. and the control runner at 2000 R. P. M., effected by providing the required tooth ratio on the drive sprockets 307 and 312, shown in Fig. 6.

As a further illustration of the possibilities of this machine to produce a simultaneous oppositely directed blasts of abrasive therefrom, there is shown in Fig. 11 a centrifugal blasting machine constructed in accordance with the machine shown in Figs. 1 to 3 inclusive, except that the control runner 40 is provided with eighteen equally spaced discharge passages or ports 45 and the throwing rotor 10 is provided with sixteen equally spaced discharge passages or ports 15. By rotating the throwing rotor 10 at 2250 R. P. M. and the control runner 40 at 2000 R. P. M., controlled firing in two opposite directions from the same throwing rotor 10 is obtained.

The direction of discharge of the streams is, of course, determined by the clockdial position at which the discharge passages or ports in the control runner and the discharge passages or ports in the throwing rotor move into alignment, so as to deposit abrasive on the advancing passages or blades of the throwing rotor. Once the abrasive has been deposited in the discharge passages or on the throwing blades of the throwing rotor, the abrasive will be centrifugally

thrown by the advancing faces thereof in a direction determined by the length of the discharge passages or blades, the smoothness of the discharge passages, and other factors which are constants of the particular machine.

Thus it will be appreciated that accurate and controlled firing in one direction only or in two or more predetermined directions from the same machine can be attained by providing the control runner and throwing rotor with the proper number of discharge passages or ports and rotating the runner and rotor at speeds which are in inverse ratio to the number of discharge passages or ports therein. Upblast or downblast, or both upblast and downblast, a three o'clock sideblast or a nine o'clock sideblast, or both a three o'clock and a nine o'clock sideblast, may be attained with a machine constructed as above described.

The throwing rotor may be of any desired diameter, preferably ranging from nine to thirty inches, and the throwing blades or passages on the throwing rotor may be of any desired radial length and, if desired, may be of such length as to extend close to the axis of rotation providing only a sufficient central opening in the rotor to make room for the control runner positioned therein. When the blades of the throwing rotor are of substantial length, it is obvious that wear on the control runner and the rotor sleeve may be correspondingly reduced with greater wear concentrated on the throwing blades of the rotor, which may be made removable and replaceable. If the throwing blades or discharge passages of the throwing rotor are of relatively short radial length with a corresponding increase in diametric size of the control runner, the control runner, and particularly the blades or discharge passages thereof which will then receive some wear, may be made removable and replaceable, as is obvious to those skilled in the art.

The abrasive receives its final abrading velocity from the advancing faces of the rotor blades or segments and the advancing faces or surfaces thereof are preferably made removable so that these parts can be replaced when worn. The parts of the machine which receive tensile strains and shocks may be made of a high grade of steel, and the parts subjected to wear may be made of a suitable wear-resisting metal.

The directional control adjustment of the machine may be made by a slight shift adjustment of the rotor on its supporting shaft or the runner on its supporting shaft, or the adjustment can be effected by a slight rotative shift of one of the driving sprockets or gears connected either to the rotor shaft, the runner shaft or to the power transmission shaft.

Actual tests have demonstrated that a high degree of directional control may be attained by a machine constructed as herein disclosed. The abrasive is given a uniformly accelerated velocity by the runner which finally discharges abrasive therefrom into the rotor passages or upon the inner ends of the rotor blades as they move into alignment with the respective runner passages or blades. The speed of the abrasive when discharged from the runner passages or blades into or on the rotor passages or blades is a speed which closely approaches the speed of the rotor passages or blades, so that the abrasive is received upon the advancing face of the rotor blades or segments at approximately the speed of travel thereof. If the runner is made with one less blade or passage than the number provided in the rotor, the peripheral velocity of the run-

ner passages or blades is actually greater than the speed of the inner ends of the rotor blades or passages, so that the abrasive is delivered onto the runner blades or passages substantially without shock as a result of the transfer. Actual test has demonstrated that the quantity of abrasive break-up and the amount of blade wear in this machine is substantially less than that occurring in prior art centrifugal blasting machines including the well-known control cage and impeller type of machine. The blades or throwing segments in the rotor and runner thus have long life in use and little or no abrasive break-up results during movement of the abrasive through the machine.

A further advantage of the machine herein disclosed resides in the great accuracy with which the direction of discharge may be controlled in any desired clockdial position, whether the target, comprising the steel sheet, casting or forging, is positioned below or above the machine, to either side of the machine, or at any other relative position. Directional firing can be controlled within 5° or less.

Another great advantage of the machine herein disclosed is the great uniformity in the blast pattern produced. The abrasive is distributed uniformly over the entire width of the rotor blades or segment, producing more uniform wear on each of these blades or segments, with a resulting full width impingement pattern on the target. The length of the impingement pattern on the target can be easily fixed and determined by varying the peripheral length of the discharge passages in the rotor or the peripheral length of the discharge passages in the runner or by varying the length of both, so that the discharge passages in the runner and rotor are in partial or complete alignment over a longer or shorter arc during rotation. It will be appreciated that where the discharge passages in the rotor or runner or both are of greater peripheral length, these passages will remain in partial or full alignment over a greater arc during synchronized rotation of the runner or rotor. Thus by varying the peripheral length of the passages in the runner or rotor or both, an impingement pattern on the target of almost any desired length can be obtained within the capacities of the machine.

It will be further appreciated that when an impingement pattern of substantial length is desired, it may be effected by enlarging the peripheral length of the passages in the runner or rotor or both, and more abrasive can be fired by the machine so that the same intensity of impingement can be attained over the entire length and width of a longer impingement pattern as over a shorter one, a result which cannot be attained by centrifugal blasting machines now known or in use. Where an impingement pattern of approximately twenty inches in length is desired from a rotor having a diameter of approximately twenty inches, the machine will directionally discharge without overloading as much as 300 lbs. of abrasive per minute, or more. A longer impingement pattern with the same impingement intensity is obtained by increasing the peripheral length of the discharge passages in the rotor or runner or both, the machine then having a correspondingly increased abrasive throwing capacity, since obviously more abrasive can be discharged through a larger discharge passage than a smaller one. The width of the impingement pattern can also be determined as desired by increasing the width of the discharge

passages or blades in the rotor and runner with the assurance that the full blade width of both rotor and runner will be utilized in throwing abrasive.

5 It is understood that where the term "abrasive" is herein used, it is intended to refer to steel shot or grit, quartz sand and other granular materials commonly used in the blast cleaning of castings, forgings, bars, sheets and like metallic 10 materials, to remove encrusted molding sand, irregular projections, and scale from the surface thereof.

While certain novel features of the invention have been disclosed and are pointed out in the 15 annexed claims, it will be understood that various omissions, substitutions and changes may be made by those skilled in the art without departing from the spirit of the invention.

What is claimed is:

20 1. A centrifugal abrasive blasting machine operable to throw a concentrated stream of abrasive over a predetermined limited arc including, a rotatably mounted rotor having a plurality of 25 equally spaced abrasive discharge passages extending inwardly short of the axis of rotation thereof defining a central space, a rotatably mounted control runner positioned within said central space and having its axis of rotation in alignment with the axis of rotation of said rotor, said control runner having a plurality of 30 equally spaced abrasive discharge passages differing in number from the number of discharge 35 passages in said rotor, means for supplying abrasive to the discharge passages of said runner, and driving means operable to rotate said rotor and runner at speeds which are in inverse ratio to the number of discharge passages in said rotor and runner respectively so as to move the successive 40 passages in said runner into discharging alignment with the successive passages in said rotor at a predetermined clockdial position during 45 rotation.

2. A centrifugal abrasive blasting machine operable to throw two oppositely directed concentrated streams of abrasive each discharged over 45 a predetermined limited arc including, a rotatably mounted rotor having a plurality of 50 equally spaced abrasive discharge passages which extend inwardly short of the axis of rotation thereof defining a central space, a rotatably mounted control runner positioned within said central space with the axis of rotation of said runner in substantial alignment with the axis of rotation of said rotor, said control runner having a plurality of 55 equally spaced abrasive discharge passages differing in number by two from the number of discharge passages in the throwing rotor, means for supplying abrasive to the discharge passages of said runner, and means for rotating said rotor and runner in timed relation and at speeds which are in inverse ratio to the number of discharge passages in said rotor and runner respectively.

3. A centrifugal abrasive blasting machine operable to throw a concentrated stream of abrasive over a predetermined limited arc including, a rotatably mounted rotor having a plurality of 60 equally spaced abrasive discharge passages, a rotatably mounted control runner having a plurality of 65 equally spaced abrasive discharge passages therein differing in number from the discharge passages of the throwing rotor, said runner having its axis of rotation concentric with the axis of rotation of said rotor with the outer 70 ends of the passages in the runner positioned

adjacent the inner ends of the passages in the rotor, means for supplying abrasive to the discharge passages of said runner, and driving means operable to rotate said rotor and runner in timed relation and at speeds which are in inverse ratio to the number of discharge passages in said rotor and runner respectively so as to move the discharge ends of the successive passages in said runner into discharging alignment with the inner ends of the successive passages in said rotor at a predetermined clockdial position during rotation.

4. A centrifugal blasting machine operable to throw a concentrated stream of abrasive over a predetermined limited arc including, a rotor comprising a rotatably mounted side wall member having a plurality of throwing elements supported by said side wall member defining equally spaced abrasive discharge passages therebetween, a control runner comprising a rotatably mounted side wall member having a plurality of throwing elements mounted thereon defining equally spaced abrasive discharge passages therebetween with the discharge passages in said runner differing in number from the discharge passages in said rotor, said runner having its axis of rotation substantially concentric with the axis of rotation of said rotor with the outer ends of the passages in the runner positioned adjacent the inner ends of the passages in said rotor, means for supplying abrasive to the discharge passages in said runner, and driving means operable to rotate said rotor and runner in timed relation and at speeds which are in inverse ratio to the number of discharge passages in said rotor and runner respectively so as to move the discharge passages in said runner into discharging alignment with the successive passages in said rotor at a predetermined clockdial position during rotation.

5. A centrifugal blasting machine operable to throw a concentrated stream of abrasive over a predetermined limited arc including, a rotor comprising a rotatably mounted side wall member and an overhanging rim supported by said side wall member having equally spaced discharge ports therein, a control runner fitting within said rim comprising a rotatably mounted side wall member whose axis of rotation is concentric with the axis of rotation of said rotor, and a laterally extending rim supported by the side wall member of said runner and positioned adjacent the inner periphery of said rotor rim, said runner rim having equally spaced discharge passages therein differing in number from the discharge passages in said rotor rim, means for supplying abrasive to the discharge passages of said runner, and means for rotating said rotor and runner in timed relation and at speeds which are in inverse ratio to the number of discharge passages in said rotor and runner respectively.

6. A centrifugal blasting machine operable to throw a concentrated stream of abrasive over a predetermined limited arc including, a rotatably mounted shaft, a rotor having equally spaced abrasive discharge passages supported on said shaft, a second shaft having its axis of rotation substantially concentric with the axis of rotation of said first shaft, a control runner mounted on said second shaft having equally spaced abrasive discharge passages differing in number from the number of discharge passages in said rotor, said runner being arranged so that the outer ends of the runner discharge passages are positioned adjacent the inner ends of said rotor discharge pas-

sages, means for supplying abrasive to the discharge passages in said runner, and driving mechanism operably connected to said shafts whereby said rotor and runner can be rotated in timed relation and at speeds which are in inverse ratio to the number of discharge passages in said rotor and runner respectively so as to move the successive passages in said runner into discharging alignment with the successive passages in said rotor at a predetermined clockdial position during rotation.

7. A centrifugal abrasive blasting machine operable to throw a concentrated stream of abrasive over a predetermined limited arc including, 15 a rotor having equally spaced abrasive discharge passages extending inwardly short of the axis of rotation thereof to define a central space, a rotatably mounted shaft fixed to said rotor, a control runner positioned within said central space having equally spaced abrasive discharge passages therein differing in number from the number of discharge passages in said rotor, a second rotatably mounted shaft fixed to said runner having its axis of rotation concentric with the axis of rotation of said rotor shaft, a drive pulley adapted to be connected to a power source, and mechanism operably connecting said pulley to said shafts whereby said shafts may be rotated at speeds which are in inverse ratio to the number of discharge passages in said rotor and runner respectively so as to move successive passages in said runner into discharging alignment with successive passages in said rotor at a predetermined clockdial position during rotation.

35 8. A centrifugal blasting machine operable to throw a concentrated stream of abrasive over a predetermined limited arc including, a rotor having equally spaced abrasive discharge passages therein extending inwardly short of the axis of rotation thereof to define a central space, a rotatably mounted drive shaft having one end thereof fixed to said rotor, a control runner positioned within said central space having equally spaced abrasive discharge passages therein differing in number from the number of discharge passages in said rotor, a second rotatably mounted drive shaft having one end thereof fixed to said runner, said runner shaft having its axis of rotation substantially concentric with the axis of rotation of said rotor shaft, a power transmission shaft, means operably connecting the power transmission shaft to said runner shaft and rotor shaft, and a drive pulley operably connected to one of said shafts, said means connecting said transmission shaft to said rotor and runner shafts being operative to establish a drive ratio between said runner shaft and rotor shaft which is in inverse proportion to the number of passages in said rotor and runner respectively.

60 9. A centrifugal blasting machine operable to throw a concentrated stream of abrasive over a predetermined limited arc including, a rotor having equally spaced abrasive discharge passages therein extending inwardly short of the axis of rotation thereof to define a central space, a rotatably mounted tubular drive shaft having one end thereof fixed to said rotor, a control runner positioned within said central space having equally spaced abrasive discharge passages therein differing in number from the number of discharge passages in said rotor, a second rotatably mounted drive shaft positioned within said tubular drive shaft having one end thereof fixed to said runner, said runner shaft having its axis of rotation substantially concentric with the axis

of rotation of said rotor shaft, means for supplying abrasive to said runner passages, and driving mechanism operably connected to said shafts whereby said rotor and runner may be rotated in timed relation and at speeds which are in inverse ratio to the number of discharge passages in said rotor and runner respectively so as to move the successive passages in said runner into discharging alignment with the successive passages in said rotor at a predetermined clockdial position during rotation.

10. A centrifugal abrasive blasting machine operable to throw two oppositely directed concentrated streams of abrasive each discharging over a predetermined limited arc including, a rotatably mounted rotor having an even number of equally spaced abrasive discharge passages therein which extend inwardly short of the axis of rotation thereof to define a central space, a rotatably mounted control runner positioned within said central space and having its axis of rotation substantially in alignment with the axis of rotation of said rotor, said control runner having an even number of equally spaced abrasive discharge passages therein two more in number than the number of discharge passages in the throwing rotor, means for supplying abrasive to said runner passages, and means for rotating said rotor and runner in timed relation and at speeds which are in inverse ratio to the number of discharge passages in said rotor and runner respectively so as to move the successive passages in said runner into discharging alignment with the successive passages in said rotor at two predetermined opposite clockdial positions during rotation, said rotor and runner having cooperating elements rotating therewith blocking escape of abrasive from said runner passages into said rotor passages except at said predetermined clockdial positions.

11. A centrifugal abrasive blasting machine operable to throw two oppositely directed concentrated streams of abrasive each discharging over a predetermined limited arc including, a rotatably mounted rotor having an even number of equally spaced abrasive discharge passages therein which extend inwardly short of the axis of rotation thereof to define a central space, a rotatably mounted control runner positioned within said central space and having its axis of rotation substantially in alignment with the axis of rotation of said rotor, said control runner having an even number of equally spaced discharge passages therein two less in number than the number of discharge passages in the throwing rotor, means for supplying abrasive to said runner passages, and means for rotating said rotor and runner in timed relation and at speeds which are in inverse ratio to the number of discharge passages in said rotor and runner respectively so as to move the successive passages in said runner into discharging alignment with the successive passages in said rotor at two predetermined opposite clockdial positions during rotation, said rotor and runner having cooperating elements rotating therewith blocking escape of abrasive from said runner passages into said rotor passages except at said predetermined clockdial positions.

12. A centrifugal abrasive blasting machine operable to throw a concentrated stream of abrasive over a predetermined limited arc including, a rotatably mounted rotor having a plurality of equally spaced circumferentially extending segments defining abrasive discharge passages there-

between, a rotatably mounted runner having its axis of rotation in substantial alignment with the axis of rotation of said rotor, said runner having a plurality of equally spaced circumferentially extending segments defining abrasive discharge passages therebetween differing in number from the number of discharge passages in said rotor, said runner being arranged so that the outer ends of the runner discharge passages are positioned adjacent the inner ends of said rotor discharge passages, means for supplying abrasive to said runner passages, and driving means operable to rotate said rotor and runner in timed relation and at speeds which are in inverse ratio to the number of discharge passages in the said rotor and runner respectively so as to move said passages in said runner into discharging alignment with the successive passages in said rotor at a predetermined clockdial position during rotation, said rotor and runner segments cooperating to block the escape of abrasive from said runner passages into said rotor passages except at said predetermined clockdial position.

13. A centrifugal abrasive blasting machine operable to throw a concentrated stream of abrasive over a predetermined limited arc including, a rotatably mounted rotor having a plurality of equally spaced circumferentially extending segments defining abrasive discharge passages therebetween, a rotatably mounted runner having its axis of rotation in substantial alignment with the axis of rotation of said rotor, said runner having a plurality of equally spaced circumferentially extending segments defining abrasive discharge passages therebetween differing in number from the number of discharge passages in said rotor, said runner being arranged so that the outer ends of the runner discharge passages are positioned adjacent the inner ends of the rotor discharge passages, means for supplying abrasive to said runner passages, said rotor segments having an abrasive receiving cavity in the inner facing surface thereof positioned between each pair of adjacent abrasive discharge passages defined by said segments, and driving means operable to rotate said rotor and runner in timed relation and at speeds which are in inverse ratio to the number of discharge passages in said rotor and runner respectively so as to move successive runner passages into discharging alignment with successive rotor passages at a predetermined clockdial position during rotation.

14. A centrifugal blasting machine operable to throw a concentrated stream of abrasive over a predetermined limited arc including, a rotatably mounted rotor having a plurality of equally spaced circumferentially extending segments defining abrasive discharge passages therebetween, said segments each having a generally arcuate shaped inner end defining therebetween a central space of generally circular form, a rotatably mounted runner positioned within said central space and having its axis of rotation substantially concentric with the axis of rotation of said rotor, said runner having a plurality of equally spaced circumferentially extending segments defining abrasive discharge passages therebetween differing in number from the number of discharge passages in said rotor, means for supplying abrasive to said runner passages, and driving means operable to rotate said rotor and runner in timed relation and at speeds which are in inverse ratio to the number of discharge passages in said rotor and runner respectively

so as to move successive runner passages into discharging alignment with successive rotor passages at a predetermined clockdial position during rotation.

15. A centrifugal blasting machine operable to throw a concentrated stream of abrasive over a predetermined limited arc including, a rotatably mounted rotor having a plurality of equally spaced radially arranged throwing blades extending inwardly short of the axis of rotation of said rotor to define a central space, a tubular sleeve extending into said space fixed to rotate with said blades, said sleeve having an abrasive passage in the tubular side wall thereof adjacent the inner end of each of said blades, a rotatably mounted control runner fitting within said sleeve and having its axis of rotation substantially concentric with the axis of rotation of said sleeve, said runner comprising a tubular member having equally spaced discharge passages in the tubular side wall thereof differing in number from the number of discharge passages in said rotor sleeve, means for supplying abrasive to said runner passages, and driving means operable to rotate said rotor and runner in timed relation and at speeds which are in inverse ratio to the number of discharge passages in said rotor and runner respectively so as to move successive runner passages into discharging alignment with successive rotor passages at a predetermined clockdial position during rotation.

16. A centrifugal blasting machine operable to throw a concentrated stream of abrasive over a predetermined limited arc including, a rotatably mounted rotor comprising spaced side wall members, a plurality of equally spaced segments supported by said side wall members extending inwardly short of the axis of rotation of said rotor defining a central space, said rotor segments defining abrasive discharge passages therebetween, a control runner fitting within the central space defined by said rotor segments and having its axis of rotation substantially concentric with the axis of rotation of said rotor, said runner comprising spaced side wall members, equally spaced passage-defining segments fixed to said runner side walls extending inwardly short of the axis of rotation of said runner to define a central space, said runner passage differing in number from the number of passages in said rotor, means for supplying abrasive to the central space and passages of said runner, and driving means operable to rotate said rotor and runner in timed relation and at speeds which are in inverse ratio to the number of discharge passages in said rotor and runner respectively so as to move successive runner passages into discharging alignment with successive rotor passages at a predetermined clockdial position during rotation.

17. A centrifugal blasting machine operable to throw a concentrated stream of abrasive over a predetermined limited arc including, a rotatably mounted rotor having a plurality of equally spaced radially extending throwing blades extending inwardly short of the axis of rotation of said rotor to define a central space, a tubular sleeve extending into said space fixed to rotate with said blades, said sleeve having an abrasive passage in the tubular side wall thereof adjacent the inner end of each of said blades, a rotatably mounted control runner snugly fitting within

said sleeve and having its axis of rotation substantially concentric with the axis of rotation of said sleeve, said runner comprising a tubular member having equally spaced discharge passages in the tubular side wall thereof differing in number from the number of discharge passages in said rotor sleeve, said rotor sleeve having an abrasive-receiving cavity in the inner facing surface thereof positioned between each pair of adjacent abrasive discharge passages therein, means for supplying abrasive to said runner passages, and driving means operable to rotate said rotor and runner in timed relation and at speeds which are in inverse ratio to the number of discharge passages in said rotor and runner respectively so as to move successive runner passages into discharging alignment with successive rotor passages at a predetermined clockdial position during rotation.

20 18. A centrifugal abrasive blasting machine operable to throw a concentrated stream of abrasive over a predetermined limited arc including, a rotatably mounted rotor having equally spaced abrasive discharge passages extending inwardly short of the axis of rotation thereof defining a central space, a rotatably mounted control runner positioned within said central space and having its axis of rotation substantially concentric with the axis of rotation of said rotor, said runner having a plurality of equally spaced abrasive discharge passages differing in number from the number of discharge passages in said rotor, means for supplying abrasive to the discharge passages of said runner, and driving means operable to rotate said rotor and runner in timed relation and at speeds which are in inverse ratio to the number of discharge passages in said rotor and runner respectively so as to move successive runner passages into discharging alignment with successive rotor passages at a predetermined clockdial position during rotation, the length of path swept by the fired abrasive being determined by the peripheral length of the discharge passages in said rotor or runner or both.

25 19. A centrifugal blasting machine operable to throw a concentrated stream of abrasive over a predetermined limited arc including, a rotatably mounted rotor having a plurality of equally spaced abrasive discharge passages extending inwardly short of the axis of rotation thereof defining a central space, a rotatably mounted control runner positioned within said central space and having its axis of rotation substantially concentric with the axis of rotation of said rotor, said runner having a plurality of equally spaced abrasive discharge passages differing in number from the number of said rotor discharge passages, means for supplying abrasive to said runner discharge passages, driving means operable to rotate said rotor and runner in timed relation and at speeds which are in inverse ratio to the number of discharge passages in said rotor and runner respectively so as to move successive runner passages into discharging alignment with said rotor passages at a predetermined clockdial position during rotation, and means for adjusting the clockdial aligned position of said rotor and runner passages to determine the direction of discharge of the abrasive fired from said rotor.
